UNITED STATES PATENT OFFICE.

BENJAMIN F. HART, JR., OF HOBOKEN, NEW JERSEY.

COOLING-TOWER.

No. 902,875.

Specification of Letters Patent.

Patented Nov. 3, 1908.

Application filed June 17, 1907. Serial No. 379,514.

To all whom it may concern:

Be it known that I, BENJAMIN F. HART, Jr., a citizen of the United States, residing at Hoboken, in the county of Hudson and State of New Jersey, have invented certain new and useful Improvements in Cooling-Towers, of which the following is a specification.

My invention relates to water towers whose function is to cool water by exposing the same in a more or less finely divided state to the action of the atmosphere for aeration and evaporation. Water towers of this type have been constructed wherein a series of shallow pans with specially perforated bottoms are held suspended at suitable distances one above the other and the water being delivered into the topmost one is allowed to drop in fine particles from one pan to the next until a collecting pan at the bottom is reached, it having been in the meantime cooled and aerated by thorough and extended contact with the atmosphere.

In such apparatus it is evident that unless preventive means are employed, considerable quantities of the water in dripping from one pan to another will be blown entirely out of the apparatus by currents of air; also since the fall between pans is in practice about seven feet, the water in falling into a pan will splash to a considerable height, found by observation to be between two and three feet and thus escape from the pan.

It is the object of the present invention therefore to provide an improved apparatus of this character wherein a novel form of wind shield which also serves as a spray catcher is employed, a further object is to provide a simple and efficient means whereby loss of water from splashing is prevented and the water kept in its downward course through the tower.

Other objects and advantages of my improved construction in details will appear from the following description of a preferred form thereof, taken in connection with the accompanying drawings and the same will finally be more particularly pointed out in the appended claims.

Like reference characters designate corresponding parts in each view.

Figure 1, is a side elevation showing a

water tower with my improved device applied thereto. Fig. 2 is an end elevation. Fig. 3 is an enlarged fragmentary detail view partly in section of the top of the apparatus and showing features of construction which are duplicated in each of the sections. Fig. 4 is a plan view of Fig. 3.

1 is a suitable tower or framework which may be of various designs in cross section; it is preferably rectangular and may be either square or oblong. This tower will of course be suitably braced and it carries a series of decks to support the several pans.

2 is a pipe for supplying the fluid to be cooled to the top of the apparatus; this pipe will usually in practice be a discharge conduit from an ammonia or other condenser. Said pipe has an outlet 3 at the top of the tower for discharging into the topmost pan 4 of the series. The remaining pans 5, 6, 7, and 8 with the final collecting pan 9 are arranged on the decks of the tower or framework and spaced apart about seven feet.

A discharge pipe 10 conveys the water from the collecting pan 9 back to the place of use after the same has been cooled and aerated by the action of the apparatus. The water pans may be made of sheet metal and provided with bottoms so perforated and arranged with deflecting flutes or the equivalent thereof as to cause the water in dropping therethrough to be deflected from each side and converge in the center, thus making intersecting streams and still further exposing the particles to atmospheric influence. This type of perforated pan bottom is not claimed herein and hence is not specifically illustrated.

My improved wind shield and spray catcher consists of a series of aprons or plates 11, 12, 13 and 14 alternately disposed upon opposite sides of the tower and extending upwardly and outwardly adjacent the pans as shown. It will be observed that a considerable space, in practice about three feet, is left open under the bottom of the shield and that as the shield is deflected outwardly, there is also a large space between its top and the next upper pan deck. This space is about four feet in width so that the sum of it and the space underneath approximately equals the distance between

the pan decks. These aprons are preferably constructed of galvanized iron plates and are securely held in proper position by iron straps as illustrated at 11'.

5 As will be seen by reference to Fig. 3 the lower edge of the aprons or shields are upturned inwardly so as to form gutters 15, and from these leader pipes 16 extend inwardly and are arranged to discharge into the next lower pan.

As will be apparent the purpose of this arrangement is to collect the spray thrown against the shields and conduct the same back into the pans.

15 A ladder 17 may be disposed upon a side of the tower for ready access to the same.

A further feature of importance in the present invention consists in a novel means whereby the splashing of the water falling into a pan are retained therein and thereby waste from this cause prevented. Since the water falls about seven feet between pans it will be observed that splashes will arise to a considerable height which I have found to 25 be a maximum of about three feet. To retain this water I provide a fine wire screen 18, around the outside edge of the cooling pans and extend the same up therefrom far enough to catch all splash, or about three 30 feet as above noted. These screens may be secured in place by iron flaps 18' bolted to the sides of the pan.

I have illustrated by arrows the directions which the currents of air striking the tower 35 are caused to take by my improved wind shield and it will be seen that I have provided an arrangement which while it allows the greatest freedom of circulation for the air in contact with the particles of water, 40 effectively prevents waste of water by the spraying of the same outside the apparatus.

It will be seen that when the wind blows in the direction as indicated by the arrows on Figs. 1 and 2 the shields 11, and 13, 45 catch the spray and return to the next lower tray by spouts 16. The wind striking the shields 12 and 14 is deflected and passes downward across the next tray and strikes the opposite shield as indicated. So no matter what direction the wind blows the spray carried by the same will be intercepted by a shield and returned to one of the trays.

Having thus described my invention, what I claim as new and desire to secure by Letters Patent is as follows:

1. A cooling tower comprising a supporting framework, a series of water pans arranged at intervals thereon and having means to discharge from one to another, and 60 a series of inclined aprons extending upwardly and outwardly, laterally of said pans, said inclined aprons being arranged to

leave substantial openings above and below the same through the tower.

2. A cooling tower comprising a supporting framework, a series of water pans arranged at intervals thereon and having means to discharge from one to another, and a series of inclined aprons arranged alternately upon opposite sides of the tower, said 70 aprons extending upwardly and outwardly adjacent the spaces between the pans.

3. A cooling tower comprising a supporting framework, a series of water pans arranged at intervals thereon and having means to discharge from one to another, a series of inclined aprons extending upwardly and outwardly adjacent the tower, gutters formed along the bottoms of said aprons, and means to direct the discharge 80 from said gutters back into the pans.

4. A cooling tower comprising a supporting framework, a series of water pans arranged at intervals thereon, said pans being provided with foraminous bottoms, inclined 85 aprons secured alternately to opposite sides of the tower adjacent the pans, said aprons extending upwardly and outwardly and means to direct spray falling upon said aprons back into the pans.

5. A cooling tower comprising a supporting framework, a series of water pans arranged at intervals thereon and having means to discharge from one to another, inclined aprons secured alternately to opposite 95 sides of the tower adjacent the pans, said aprons extending upwardly and outwardly, means to direct spray falling upon said aprons back into the pans, and means to prevent loss by splashing of water falling from 100 one pan to another.

6. A cooling tower comprising a supporting framework, a series of water pans arranged at intervals thereon and having means to discharge from one to another, inclined aprons secured alternately to opposite sides of the tower adjacent the pans, said aprons extending upwardly and outwardly, means to direct spray falling upon said aprons back into the pans, and means to 105 prevent loss by splashing, said means consisting of a foraminous guard, arranged about said pans.

7. A cooling tower comprising a supporting framework, a series of water pans arranged at intervals thereon and having means to discharge from one to another, inclined aprons secured alternately to opposite sides of the tower adjacent the pans, said aprons extending upwardly and outwardly, 110 means to direct spray falling upon said aprons back into the pans, screens arranged about the periphery of said pans and extending upwardly therefrom and flaps to se-

cure said screens in place and fixed to said pans.

8. A cooling tower comprising a supporting framework, a series of water decks arranged at intervals thereon and supporting pans adapted to discharge from one to another and a series of inclined aprons or shields attached to the outside framework of the tower and extending upwardly and outwardly opposite the intervals between

said decks; said aprons or shields being arranged to leave openings above and below same and secured to the tower structure.

In testimony whereof I affix my signature in presence of two witnesses.
